WILLIAM PARKIN, OF TAUNTON, MASSACHUSETTS, ASSIGNOR TO REED AND BARTON, OF SAME PLACE.

Design No. 3,647, dated August 31, 1869.

DESIGN FOR A PRESERVE-DISH.

The Schedule referred to in these Letters Patent and making part of the same.

To all persons to whom these presents may come:

Be it known that I, WILLIAM PARKIN, of Taunton, of the county of Bristol, and State of Massachusetts, have invented or produced a new ornamental Design for a Preserve-Dish; and do hereby declare the same to be fully represented in the accompanying drawing, which is a perspective elevation of the dish.

The said dish is of an oblong or rectangular shape, and has at the middle of each side, and also at the middle of each end, a raised panel, *a*, provided with a lion head, in *alto-relievo*.

At each corner of the dish is another raised panel,

or leg-head, *b*, having on its face a rosette or ornament in relief.

This leg-head constitutes the upper part of a leg, *c*, from which a brace, *d*, is extended to the bottom of the dish, the whole being formed in manner as represented.

I claim the ornamental design for a fruit or preserve-dish, such being as represented and described.

WILLIAM PARKIN.
